ATTORNEYS.

UNITED STATES PATENT OFFICE.

MATTHEW ADAM, OF PHILADELPHIA, PENNSYLVANIA.

SIFTING DEVICE.

Application filed March 29, 1920. Serial No. 369,654.

To all whom it may concern:

Be it known that I, MATTHEW ADAM, a citizen of the United States, residing in Philadelphia, in the county of Philadelphia and State of Pennsylvania, have invented 5 certain new and useful Improvements in Sifting Devices, whereof the following is a specification, reference being had to the accompanying drawings.

10 The invention relates to sifting devices such as may be advantageously employed in sifting ashes, gravel, etc.

The purpose of the present invention is to provide a sifting device which is simple in 15 construction and operation, and by which the sifting may be accomplished by aid of a washing liquid, in a sanitary and efficient manner without liberation of any dust whatever.

20 The invention is further directed to a sifting device operative upon the principle above noted, and which comprehends certain novel structural characteristics by which 25 disassembly of the various constituent parts may be readily effected to permit charging and discharging, and the removal from time to time of the siftings.

In the drawings, Fig. I, is a longitudinal sectional elevation of a sifting device conveniently embodying my invention.

Fig. II, is a vertical cross sectional view of the same along the plane of the arrows II-II in Fig. I. Fig. III, is a detail sectional view indicated by the arrows III-III 35 in Fig. II.

In its simplest form, my invention consists essentially of a receptacle 1, containing a washing liquid, and which I will term for convenience a precipitating tank; and a 40 sieve 2, for the material to be sifted, said sieve being capable of movement within the tank in such manner that the sifting of the dust or the finer particles from the more bulky contents of the material may be accomplished by what may be termed a leaching 45 action of the washing liquid. I have found that the process of sifting in accordance with the above principle may be effected most efficiently by intermittently steeping

50 the sieve and its contents into the washing liquid. Such motion of the sieve may be obviously effected in a number of different ways, one construction which has been found thoroughly satisfactory in practice having

been arbitrarily chosen for the purposes of 55 illustration herein.

Referring once more to the drawings, it will be observed that the sieve is mounted to revolve about an eccentric axis consisting of a shaft 3, which is journaled in notches 4, 4, formed in the upper edges of the side walls of the tank 1. By this construction, the sieve may be readily removed bodily for charging or discharging.

At one side of the device, the shaft 3, is 60 provided with a crank handle 5, and upon the other side with a collar 6, the latter being cooperative with the hub of the crank handle in preventing lateral displacement of the sieve mounting with respect to the 65 side walls of the tank. The sieve is preferably of a substantially semi-circular cross section, and provided with cover lids 7, 7, which may be attached in any desired manner. In the present instance, these cover lids are 70 hinged about the shaft 3, and adapted to be held closed by spring latches 8, 8. In operation, as the crank handle 5, is turned, it will be seen that the sieve is intermittently 75 steeped into the washing liquid and lifted 80 out of it to drain so that the dust and finer particles of material are extracted by the leaching action of the water, and precipitated in the bottom of said tank.

In order that accumulation of the precipitated siftings may be readily removed from 85 time to time, I have provided an insert tray screen 10, of fine wire mesh, said screen being disposed adjacent the bottom of the tank 1, and provided at its ends with extended 90 lifting straps, which at their upper ends, are bent outwardly to form handles 12, 12, adapted to overhang the top edges of the end walls of the tank 1. The device may be further provided with a removable cover lid 95 13 for closing the tank 1 and enclosing the rotatable sieve 2 within it, which is preferably curved in form, and provided with handles 15, 15, whereby it may be readily lifted to permit removal of the sieve for loading 100 and unloading as previously noted.

Having thus described my invention, I claim:

1. A sifting device comprising a precipitating tank for a washing liquid; a sieve for the material to be sifted, adapted to revolve in said precipitating tank; and a removable screen for receiving the precipitated sift-

ings, said screen being disposed adjacent to the bottom of the tank and provided with extended straps having lateral handle members overhanging the upper edges of said tank.

2. A sifting device comprising a precipitating tank for washing liquid; a closed sieve for the material to be sifted mounted to rotate about an eccentric axis journalled at the upper edge of the tank and readily removable therefrom; and an insert tray in the tank beneath the sieve readily removable upward from the tank after removal of the sieve.
3. A sifting device comprising, a precipitating tank for containing washing liquid, a substantially semi-circular sifter, and a shaft mounted in the tank and secured to the sifter at a point coincident with its flat side, so that when the tank is filled to a level co-

inciding with the flat side of the sifter when the latter is arranged horizontally the sifter, upon continuous rotation in one direction upon the shaft may be alternately completely submerged and ventilated.

4. A sifting device comprising a receptacle, a shaft mounted therein, a substantially semi-elliptical sifter having its flat side open and rigidly mounted upon the shaft, and a pair of closure members pivotally mounted upon the shaft by means of interfitting ears engaging the shaft to extend in opposite directions and to close the side of the sifter.

In testimony whereof, I have hereunto signed my name at Philadelphia, Pennsylvania, this 24th day of March, 1920.

MATTHEW ADAM.
